T. P. PETERSON

SPARK PLUG

Filed Nov. 2, 1920

12 Inventor.
Theodore P. Peterson
by Robert W. Jenner
Attorney.

UNITED STATES PATENT OFFICE.

THEODORE P. PETERSON, OF WESSINGTON SPRINGS, SOUTH DAKOTA.

SPARK PLUG.

Application filed November 2, 1920. Serial No. 421,808.

To all whom it may concern:

Be it known that I, THEODORE P. PETERSON, a citizen of the United States, residing at Wessington Springs, in the county of 6 Jerauld and State of South Dakota, have invented certain new and useful Improvements in Spark Plugs, of which the following is a specification.

This invention relates to spark plugs for 10 igniting the combustible charges in the power cylinders of internal combustion engines; and it consists in the novel construction and combination of the parts herein-after fully described and claimed.

15 In the drawings, Figure 1 is a vertical section through a spark plug constructed according to this invention and drawn to a greatly enlarged size for clearness. Fig. 2 is a plan view, taken in section on the line 2—2 in Fig. 1. Fig. 3 is a similar section, taken on the line 3—3 in Fig. 1.

The body portion 5 of the plug has a 20 screwthreaded portion 6 for connecting it to the engine cylinder in the usual way. A chamber 7 is formed in the upper part of the plug body, and is closed by a cap 8. The cap 8 has a screwthreaded portion 9 for securing it to the plug body, and 10 is a packing washer for keeping it gas tight. 25 The cap 8 may however be secured in any other approved way.

Rod electrodes 12 are provided, and are 30 arranged symmetrically in the chamber 7 with their lower end portions, projecting from it. Three electrodes are shown, arranged in triangular form, but two electrodes may be used, or as many more than three as 35 may be found advantageous. The electrodes 12 have offset upper end portions 14 which are secured in tapering shanks 15. These shanks 15 are secured in tapering insulators 16 of any approved insulating material, and mica may be used for that purpose. The upper end portions of the shanks and the tubular insulators project through tapering holes in the cap 8, and are secured in a block 17 of insulating material.

The block 17 is preferably formed of a 40 series of thin plates of mica. The shanks and insulators are anchored in the block by means of projecting plates 18 secured to the tops of the shanks by nuts 19 or other fastening devices. The anchor plate 18' of

one shank is provided with a stem or rod 20 which projects centrally from the block, and 25 has a screwthreaded portion 21 on its upper part.

A washer plate 24 rests on the top plate of mica, and the plates of mica are held in place by a nut 25 on the screwthreaded portion 21 which is connected to one line wire 26 by a nut 27. The other line wire is connected with the plug body. A ring electrode 30 is secured to the plug body by sten 31, and encircles the lower end portions of 35 the rod electrodes so that three spark gaps are formed in the example shown, and are included in the electric circuit between the wire 26 and the plug body. The sparks formed in all of these spark gaps assist 40 in igniting the combustible mixture in the cylinder, so that the same is ignited effectively.

In carrying out the invention the various parts are proportioned so as to make as 45 little waste space as possible in the chamber 7, the proportions in the drawings being arranged so as to show the parts as clearly as possible. The object of using a ring electrode on the plug body is to insure a spark 50 gap between one of the rod electrodes irrespective of the position to which the supporting cap is screwed to the plug body.

What I claim is:

1. In a spark plug, a plug body, a removable cap closing the top of the plug body, an insulated rod electrode projecting through the said cap and provided with means which prevent it from sliding upwardly, said rod electrode being adapted to form a spark gap 55 at the lower part of the plug body, a block formed of thin superposed plates of insulating material resting on the said cap, an anchor plate inclosed in the said block and secured to the rod electrode and having a 60 screwthreaded stem which projects from the block and affords a connection for the line wire, and a nut screwed on the said stem and securing the rod electrode and the said block to the cap.

2. In a spark plug, a plug body, a ring electrode secured at the lower part thereof, a removable cap closing the top of the plug body, insulated rod electrodes which form 65 spark gaps with each other and with the 70 ring electrode, said electrodes projecting

through the said cap and provided with means which prevent them from sliding upwardly, a block formed of thin superposed plates of insulating material resting on the said cap, anchor plates inclosed in the said block and secured to the rod electrodes, one of the anchor plates having a screwthreaded

stem which projects from the block and affords a connection for the line wire, and a nut screwed on the said stem and securing 10 the rod electrodes and the block to the cap.

In testimony whereof I have affixed my signature.

THEODORE P. PETERSON.
